WINDOW CHANNEL

Charles P. Schlegel, Rochester, N. Y., assignor
to The Schlegel Manufacturing Company,
Rochester, N. Y., a corporation of New York

Application February 29, 1932. Serial No. 595,753

3 Claims. (Cl. 296—44.5)

This invention relates to window channels, such for example as those employed to hold and guide the sliding window of an automobile, and pertains more particularly to the channel lining which 5 cushions the window against vibration, yet permitting it to be easily and quietly moved in the channel member.

One object of the invention is the provision of a lining of the above kind adapted for use with 10 material of an inexpensive character.

Another object is the provision of a lining of this class capable of being manufactured at a low cost.

A further object is the provision of such a lining 15 which is simple in construction, pleasing in appearance and effective in use.

To these and other ends the invention resides in certain improvements and combinations of parts, all as will be hereinafter more fully described, the novel features being pointed out in the claims at the end of the specification.

In the drawing:

Fig. 1 is a sectional view taken transversely 25 of a window channel constructed in accordance with one embodiment of the invention;

Fig. 2 is a sectional view of another embodiment;

Fig. 3 is a sectional view of another form of 30 window channel;

Fig. 4 is a sectional view of still another embodiment, and

Fig. 5 is an enlarged sectional view of the strip 35 which forms one of the cushioning pads for the channel lining illustrated in Figs. 3 and 4.

The same reference numerals throughout the several views indicated the same parts.

The present invention is embodied, in the present instance by way of illustration, in a window 40 runway comprising a channel member of substantially rigid sheet material such, for example, as sheet metal on the inner faces of which a suitable lining is arranged. This lining is provided with pads of resilient material stitched or 45 otherwise secured to the lining to provide cushioning means for the window channel. This application forms a continuation in part of my pending application Serial No. 567,247, filed October 6, 1931.

50 Referring now to the drawing, Fig. 1 shows a sheet metal channel member formed to provide a bottom 11 and side walls 12. The free edges of the side walls are rolled or reversely bent to form flanges 13. The channel member is provided with 55 a lining 15 the free edges 16 of which are dis-

posed under and held by the flanges 13. This lining preferably comprises a plain or fancy woven fabric of an inexpensive character, and of a good wearing and friction reducing quality, such for example, as broadcloth, although other material suitable for this use will occur to those skilled in this art. This lining is adapted to support a sliding glass sash and to afford a free sliding surface therefor which is not materially affected by moisture or freezing weather conditions.

As the lining or surfacing material 15 is of relatively thin material, it is preferred to provide a pad or strip of resilient material 17 interposed between the lining 15 and the sides 12 of the 70 channel member, and also between the lining and the bottom 11, if desired. In the present embodiment this pad preferably comprises a single strip of cotton batting, felt, or other similar material arranged on the inner faces of the bottom 75 11 and side walls 12, and held in place therein by the lining 15. The upper edges 18 of the pad preferably terminate below the flanges 13, as clearly illustrated in the drawing, to permit the end portions or free edges 16 of the lining to be 80 inserted under and held by the flanges 13. The pad is preferably secured to the lining by means of rows of stitching 25 and 26, which extend through the portion of the lining arranged on the side and bottom of the channel, respectively, 85 as clearly shown in Fig. 1.

In the embodiment shown in Fig. 2 the channel member is of the same construction as that illustrated in Fig. 1, and corresponding parts are designated by the same reference numerals. The 90 channel is provided with a lining 15a, preferably of the same material as the lining 15, arranged adjacent the inner faces of the channel, and having the free edges 16a thereof inserted under and held in place by the flanges 13. Cushioning 95 pads 17a and 18a are secured to the outer face of the lining 15a, as hereafter described, intermediate the lining and the walls of the channel member to space the sash engaging portions 20a of the lining from the rigid channel member. These pads are preferably made of an inexpensive material such, for example, as cotton, felt, paper, or other suitable material of like character. The pads 17a and 18a are preferably spaced to 100 provide breaks 21a, intermediate the pads, which enable the lining to be bent into channel form. The pads 18a are also preferably terminated short of the edges 16a to permit the latter to be inserted under the flanges 13a. The pads 17a and 105 18a are preferably secured to the outer face of 110

the lining by any suitable means such, for example, as rows of stitching 25a and 26a, which extend through the lining 15a and the pads 18a and 17a, respectively, to secure the pads to the 5 lining.

In the embodiment illustrated in Fig. 3, the lining 15b is preferably of the same material as the lining 15 and 15a above described, and is arranged adjacent the inner faces of the channel member with the free edges 16b thereof inserted under and held in place by the flanges 13. Resilient woven textile cushioning pads 17b and 18b, hereafter more fully described, are provided on the bottom and sides, respectively, of the channel 10 intermediate the channel member and the lining 15b, as clearly illustrated in the drawing. These pads are preferably secured to the lining 15b, as hereafter described, and space the sash engaging portions 20b thereof inwardly of the rigid channel 15 member. Breaks 21b are provided intermediate the pads to permit the lining to be bent into channel form for insertion in the channel member. The pads 18a are terminated short of the free edges 16b to facilitate the insertion of the 20 latter under the flanges 13. Rows of stitching 25b and 26b are extended through the lining 15b and the pads 18b and 17b, respectively, to secure the pads to the outer face of the lining.

From the foregoing description it is apparent 30 that each of the above described channel constructions provides a strong rigid channel member, a resilient pad for cushioning the sash and spacing parts of the same from the rigid channel member, and a friction reducing lining overlying 35 and secured to the pads, the lining being in turn securely held in place by the reversely bent flanges formed on the channel member. This lining provides a smooth sliding surface which is not affected by moisture or freezing weather conditions 40 and thus enables the glass to be easily and quietly moved in the channel member, even under severe atmospheric conditions. The use of the resilient cushioning pads gives the desired body and softness to the lining of the rigid channel to prevent rattling of the sash and to cause the lining 45 to project inwardly, as shown, to space the glass sash from the rigid flanges 13. It is evident that such an arrangement of the parts provides a channel construction which not only embodies 50 the desirable advantages of prior constructions, such as rigidity and strength, effective cushioning qualities, and a durable friction reducing surface for contacting with the glass sash; but which may be manufactured at a greatly reduced cost.

55 Referring now to Fig. 4, there is shown a further modification in which the lining 15c, of any suitable material, is arranged on the inner faces of the bottom 11 and side walls 12 of the channel member, and has the free edges 16c thereof disposed under and held in place by the flanges 13. Woven cushioning pads 17c and 18c, of the same 60 construction as the pads 17b and 18b illustrated

in Fig. 3 and hereafter described, are secured to the inner face of the lining 15c and extend inwardly therefrom to engage the side edge and the faces, respectively, of a sliding glass sash. The pads 17c and 18c are preferably slightly separated 80 to provide breaks 21c which permit the lining to be bent into channel shape for insertion in the channel member. The pads 18c are preferably terminated short of the free edge 16c to facilitate the insertion of the latter under the flanges 13. 85 The pads are secured to the inner face of the lining 15c by any suitable means such, for example, as rows of stitching 25c and 26c which extend through the lining and the pads 18c and 17c, respectively, to secure the pads to the inner face 90 of the lining.

The cushioning pads illustrated in Figs. 3 and 4 are of woven textile material formed to provide cut long pile surfaces, such as disclosed in my copending application now Patent No. 1,847,700, issued March 1, 1932, or uncut pile surfaces as described in my copending application Serial No. 400,125, filed October 16, 1929, or relatively long loops of a heavy strand material such as disclosed in my copending application Serial 95 No. 595,352 filed February 26, 1932.

While certain embodiments of the invention have been disclosed, it is to be understood that the inventive idea may be carried out in a number of ways. This application is therefore not 105 intended to be limited to the precise details described, but is intended to cover all variations and modifications thereof falling within the spirit of the invention or the scope of the appended claims.

I claim:

1. A window channel comprising a supporting channel-shaped member, textile fabric surfacing material arranged in said member for contact with the window glass, and one or more woven pads on said material between the latter and said member to provide cushioning support for the 110 glass.

2. A window channel comprising a supporting channel-shaped member, textile fabric surfacing material arranged in said member for contact with the window glass, and one or more woven pads on said material between the latter and said member, said pad or pads being of substantial thickness and formed by long, pile fibers to afford cushioning support for the glass.

3. A window channel comprising a substantially rigid channel-shaped supporting member, textile surfacing material arranged in said member for contact with the glass, and a plurality of woven pads on said material between the latter and said member, said pads being spaced to facilitate the bending of said material adjacent the channel corners and being of substantial thickness and formed by long cut pile fibers to afford cushioning support for the glass.

CHARLES P. SCHLEGEL.
